UNITED STATES PATENT OFFICE.

WILLIAM ROBERT BUTLER, OF CLEVELAND, OHIO.

EXPANDING CYLINDER GRINDER.

Application filed November 20, 1920. Serial No. 425,482.

To all whom it may concern:

Be it known that I, WILLIAM ROBERT BUTLER, a citizen of the United States, and resident of Cleveland, in the county of Cuyahoga and State of Ohio, have invented certain new and useful Improvements in Expanding Cylinder Grinders, of which I hereby declare the following to be a full, clear, and exact description, such as will enable others skilled in the art to which it appertains to make and use the same.

The objects of this invention are to provide a grinding tool for enlarging the cylinders of explosion and other reciprocating engines to adapt them to receive over-sized pistons.

The invention is particularly adapted for fitting over old and worn cylinders to adapt them to use with slightly larger pistons, thus preserving the life of the cylinder, which would otherwise have to be thrown away.

The invention comprises a longitudinally split cylindrical grinding shell, which is provided with means for holding abrasive material, such as carborundum powder or emery.

It includes means for holding the cylinder and rotating it when in use, and also means for expanding the parts and for locking the same in adjusted positions.

It includes resilient means for retaining the shell parts in assembled position, and for drawing them tightly against the adjusting means.

The invention is hereinafter described, shown in the accompanying drawings, and specifically pointed out in the claims.

In the accompanying drawings, Fig. 1 is a vertical longitudinal section of the device; Fig. 2 is a side elevation thereof; Fig. 3 is a plan thereof.

In these views, A is a longitudinally split cylindrical grinding shell, and the sectional parts are held together so that they can be introduced into the cylinder by means of circular springs, B, B, inserted in the circumferential grooves, C, C.

Abrasive material, such as carborundum powder, or emery, is enclosed in surface grooves or recesses, D, D, in the sections. The sections are provided with transverse partitions, E, E, in conical openings, F, in which the conical spreader, F, is positioned. This is adjusted by means of a screw-threaded central longitudinal shaft, G. This

shaft is enclosed in a sleeve, H, to which handles, I, I, are attached, by means of a pipe union, J.

The central rod is secured within the sleeve, H, by means of the terminal nut, K, which is further secured by means of a pin, L, so that it can not become loose and when the conical spreader is adjusted upon the rod, G, the entire tool can be rotated to grind the inner walls of the cylinder by turning the handles, I, I.

The rod, G, can be rotated at any time to adjust the conical spreader in the cylindrical shell by using a wrench upon the nut, K. The sleeve sections, after adjustment, are clamped tightly to the sleeve, H, by means of the disc, M, which is attached by screw threads, M', and a set screw, N, rigidly to the lower end of the sleeve, H, and engages a shoulder, O, formed on the inner faces of the flanges, P, P, upon the sections of the shell, A.

A clamping ring, Q, is forced down upon the outer faces of these flanges by means of the nut, R, having a ring-shaped handle, R', the parts being in this manner immovably secured together, and turn together when the handles are turned.

Having described the invention, what I claim as new and desire to secure by Letters Patent, is:

1. In a tool for the purpose described, in combination, a longitudinally split grinding cylinder, provided with spaced horizontal partitions and an inwardly extending flange at one end, said partitions each provided with a central conical opening, a conical spreader in said openings, resilient means for retaining said shell sections in place, a longitudinal adjusting screw for said spreader, a sleeve through which said screw passes, handles for said sleeve, a securing nut for securing said screw to said sleeve at their outer ends, a disc on the lower end of said sleeve engaging the inner side of said flange on said shell, and a clamping ring and nut on said sleeve above said flange.

2. A lapping-in tool, comprising a pair of relatively movable supporting members, a handle affixed to one of said members, an adjusting means associated with the other of said members, a sectional cylinder supported upon one of said supporting members, coating means supported upon the other of said supporting members for en-

larging the effective diameter of said cylinder, and locking means for holding said parts in adjusted position.

3. A lapping-in tool, comprising a tubular stem, a handle affixed to the upper end thereof, a supporting plate secured to the opposite end thereof, a rod rotatably mounted within said tubular stem, an upwardly tapered member adjustably mounted upon said rod, a plurality of cylinder sections mounted adjacent said tapered mem-

ber and having integral parts bearing thereon, flanges upon said cylinder sections and adapted to rest upon said supporting plate, and clamping means for locking said flanges upon said plate. 15

In testimony whereof, I hereunto set my hand this 23rd day of October, 1920.

WILLIAM ROBERT BUTLER.
In presence of—

JOSEPH DEEUBE,
Wm. M. MONROE.
